ART OF PRODUCING SEWED GARMENTS

Max Popper, Brooklyn, N. Y., assignor to Top-stitch Machine Corp., New York, N. Y., a corporation of New York

Original application December 28, 1934, Serial No. 759,449. Divided and this application October 7, 1935, Serial No. 43,938

2 Claims. (Cl. 112—262)

This invention is directed broadly to a method of producing a pinked and topstitched seam for sewed articles, wherein the edge portions of two sections of fabric are upturned and simultaneously pinked and then downfolded with the pinked edges facing in one direction and sewed together with a zig-zag topstitch to form an edge-folded and pinked elastic seam substantially flat on its normally exposed surface.

An object of this invention is to provide an edge-folded, zig-zag topstitched elastic seam substantially flat on the normally exposed surfaces of the garment by a single passage through an edge-folding and overedge stitching zig-zag sewing machine.

Another object of this invention is to provide an edge-trimmed and topstitched seam in successive steps of upturning, trimming and downfolding the edges of two or more sections of fabric with the trimmed edges facing in one direction and then stitching together the superposed edges of the sections of fabric by a single passage through a combined edge trimming and zig-zag sewing machine and form a uniformly symmetrical and superior non-rippable elastic seam. This application is a division of my prior copending application Serial No. 759,449, filed Dec. 28, 1934.

With the above and other objects in view, the invention will be hereinafter more particularly described and the successive steps required to carry out my method will be more fully disclosed.

The drawings show by way of illustration an embodiment of the seam and the steps of the method of making it substantially flat on the normally exposed surface.

Figure 1 is a perspective view showing the manner of placing, upturning, pinking, downfolding and uniting by zig-zag topstitching two fabric sections in successive steps and the step of blowing away the pinking clippings.

Figure 2 is a sectional view taken as on line 2—2 in Figure 1.

Figure 3 is a sectional view taken as on line 3—3 in Figure 1.

Figure 4 is a sectional view taken as on line 4—4 in Figure 1.

Figure 5 is a sectional view of a modified pinked and zig-zag topstitched elastic seam, wherein all the stitch lines pass through three layers of fabric and wherein the stitched portion of the folded edge is flattened by the transverse stitches and lies substantially flat on the normally exposed surface of the garment.

Figure 6 is a plan view of a folder that may be used for producing the seam shown in Figure 1.

Figure 7 is a side view of the folder shown in

Figure 6 set in the base-plate of the sewing machine.

Figure 8 is a sectional view of the folder shown in Figures 6 and 7, the section being taken as on line 8—8 in Figure 6.

Figure 9 is a fragmentary sectional view of the folder shown in Figures 6 to 8, inclusive, the section being taken as on line 9—9 in Figure 7.

Figure 10 is a fragmentary portion of a combined seaming and pinking machine which I presently consider the preferred embodiment of mechanism for carrying out my method. The sewing machine is of the zig-zag type and is well known in the art as a Singer 107W. A front elevation of my improved pinking mechanism is shown applied thereto. This figure also shows a sectional view of a clutch which is part of the means for intermittently rotating the pinking wheel in synchronism with the feeding mechanism of the sewing machine. This view also shows an air line.

Figure 11 is a plan view of the pinking unit and shows the arm for intermittently actuating the pinking wheel.

Referring more in detail to the drawings, the method is carried out as follows: Two fabric sections 10 and 11 are positioned flat and in juxtaposed relation with the normally exposed surfaces lying on the base-plate 12 of a combined pinking and zig-zag sewing machine. The sections 10 and 11 have their edges 13 and 14 upturned to fit into guideways 15 and 16 of a folder 17. The upturned edges 13 and 14 are presented to a pinking mechanism 18. The pinking mechanism 18 preferably comprises a rotary cutter 19 having a zig-zag cutting surface and is resiliently pressed in any suitable manner against the outer surface of a rotatably mounted ball bearing or disk 20.

The pinking mechanism 18 grips the upturned edge portions 13 and 14 of the fabric sections 10 and 11. The upturned edge portions are simultaneously pinked during the movement through the pinking mechanism and are then folded down with the pinked edges in superposed relation and facing in one direction by a hemming section 22 of the folder 17 and united by topstitching 23. The stitching is preferably of the zig-zag type, the fabric being pierced successively in two different and slightly spaced longitudinal lines, the threads of the stitches extending from one line to the other at uniform angles which permits the seam to yield when the fabric sections are stretched, without any danger of tearing the thread. As shown in Figure 1 and Figure 4, it will be noted that some of the stitches 24 pass

through both sections of fabric 10 and 11 and other of the stitches 25 pass through but one of the sections 10.

The seam as illustrated in Figure 4, shows the 5 edge portion 14 of the fabric section 11 folded flat and with the edge portion 13 of the fabric section 10 lying in superposed relation on the said fold. This fold forms a reinforcement. The stitching 24 goes through a plurality of layers 10 of fabric and reinforces the seam because any 10 tendency to pull the seam apart causes the strain to act in the direction of the folded edge instead of against the selvage edges. The edge-folded overedge zig-zag stitched seam shown in Figure 15 4 is stronger than an ordinary pinking seam wherein the sections of fabric are stitched while 20 lying face to face.

It is obvious that the seam shown in Figure 4 may be made without any pinking or edge-trimming 25 and that the seam will then be edge-folded, overedge zig-zag topstitched, elastic and substantially flat on the normally exposed surface. This is accomplished by removing or placing the trimming mechanism out of operating position.

25 When two layers of fabric are pinked and stitched with the fabric sections lying flat and face to face, the stitches are visible only on the left sides of the fabric sections, that is on the normally concealed surfaces of the garment. 30 However, when two layers of fabric are pinked and stitched with one folded layer and one superposed layer, as shown in Figure 4, the stitches are visible on the left or normally concealed side as well as on the right or normally exposed side 35 of the fabric sections and such a stitch is termed by the art a topstitch.

When the edge-folded overedge zig-zag topstitched seam shown in Figure 4 is made by two 40 sewing operations, i. e., first a combined seaming and pinking operation and then a separate topstitch operation, it is practically impossible to produce uniformly parallel lines of stitching and uniformly parallel lines of pinking and stitching. My method of operating in successive steps 45 with the edge folding, edge trimming, and zig-zag topstitching performed concomitantly, makes it possible not only to produce the seam in one operation, but in addition provides parallel and uniform lines of pinking and stitching and a 50 seam which is elastic, non-rippable, and substantially flat on its normally exposed surface.

The seam shown in Figure 5 is similar to the overedge zig-zag topstitched edge-folded seam shown in Figure 4. The seam shown in Figure 5 55 has a substantial portion of the folded surface flattened by transverse stitches and is also elastic, non-rippable and substantially flat on the normally exposed surface.

As best shown in Figures 6 to 9 inclusive, an 60 embodiment of means for upturning and downfolding the fabric sections 10 and 11 may comprise the folder 17 which is provided with a central rib 26 secured to the guideway member 27 intermediate the guideways 15 and 16. A 65 guide rib 28 fixed to the base-plate 29 of the folder 17 terminates in a line with the point of exit 30 of the hemming section 22 and as close to the needle 21 as possible. The ribs 26 and 28 are in alignment. The rib 28 extends substantially 70 down to the base-plate 12 of the sewing machine. The folder 17 also comprises two plates 31 and 32 fastened to the guideway member 27 and positioned in a horizontal plane parallel with and in spaced relation from the 75 base-plate 12. The plates 31 and 32 are spaced

away from the rib 28 forming longitudinal openings 33 to permit the fabric sections 10 and 11 (Figure 1) to enter between said plates and the base-plate 12 and to turn upwards, the turned edges 13 and 14 on emerging from the guideways 15 and 16 being then constrained to follow the rib 28 on respective sides thereof till the point of exit 30 from the hemming section 22 of the folder 17, when the pinked edges are curved at the tongue 34 and then flattened in superposed relation in the horizontal slot-like passage 35 adjacent the needle 21.

Figure 7 shows the guide rib 26 pivotally mounted on a pivot 36 in the guideway member 27 which is integral with the folder base-plate 29. The guideway member 27 has a slot 37 serving to slidably support the integrally connected rib 26, and the horizontal plates 31 and 32 in pivotal relation with the folder base-plate 29. These pivotally mounted fabric folding members may thus 20 jointly swing up and down about the pivot 36. A spring 38 mounted in the central guideway member 27 reacts against the front end of the rib 26 and normally raises the said end and causes the end facing the needle 21 to press down. The horizontal plates 31 and 32 are designed to extend to and rest on the feed-dog of the combined seaming and pinking machine shown in Figure 10. During the up and down motion of the feed-dog, the plates 31 and 32 will move up and down 35 concomitantly with the feed-dog. The joint up and down motion of the plates 31 and 32 and the four-motion feed-dog mechanism acting against any fabric passing between them to the needle constitutes work feeding means.

It is to be noted that the central guide rib 26 of the folder 17 is positioned intermediate the trimming members 19 and 20 so as to direct the upfolded edges of the fabric sections in a predetermined path intermediate said members. As 4 shown in Figure 9, the central guide member 27 has curved sides 41 so as to facilitate the upfolding of the fabric sections on the folder base-plate 29.

It is to be noted that the two sections of fabric 4 10 and 11 are positioned on the base-plate 12 of the sewing machine with the normally exposed surfaces of the fabric sections in direct contact with said base-plate.

It is also to be noted that when the seam 5 herein described is incorporated in shadowproof or panel garments, that there will be a plurality of superposed sections of fabric on each side of the seam.

I may position the pinking mechanism 18 substantially in line with the needle so as to perform the pinking and stitching operations simultaneously and in adjacent relation.

In order to remove the pinked clippings from the line of stitching and away from the pinking mechanism, I provide an air compressor or blower (not shown) and terminating in an air line 40 preferably positioned close to the exit end of the pinking mechanism 18. A jet of air is thus directed crosswise to the line of pinking to blow the pinked clippings out of the way of the line of stitching.

In operation the edges of the fabric sections are first turned up and pinked, the pinked edges 7 are then downfolded in superposed relation on one of the sections of fabric and sewed together to form a pinked and zig-zag top-stitched seam. This makes an ornamented and reinforced elastic seam which can be very readily made by the 7

combined pinking and zig-zag sewing machine in one continuous operation.

It is to be noted that by the term "flat, edge-folded, seam" is meant a seam which has no hollow formation at the folded edge and wherein the folded layers are drawn together taut by the stitches which go through and across the line of seam formation, as best shown in Figure 4.

An elastic seam of the nature herein described is very desirable for making ladies' silk underwear and similar articles of fine texture where it is necessary to reinforce the seam to secure additional strength because very delicate fabrics are employed for such garments.

15 My pinking mechanism 18 comprises a bracket 44 preferably fastened to the lower portion of the head 45 of the sewing machine 42. The bracket 44 has an arm 46 carrying a pin 47 at the lower end of which has been mounted the 20 roller or ball bearing 20. An arm 48 has been mounted on a pivot 43 and has a vertical shaft 49 at the lower end of which has been mounted the rotary cutter 19. The members 19 and 20 are 25 preferably of the same diameter and are positioned so that the point of intersection of their circumferences is in line with the center of the loop taker shaft 50, of the zig-zag sewing machine with which my pinking attachment is presently shown combined, as best shown in Figure 10.

30 The horizontally swinging arm 48 may be swung to the left so that the rotary cutter 19 contacts in operative relation with the rotary member 20. The rotary cutter is adapted to be swung horizontally to the right away from the needle so 35 as to permit the threading of the needle. For the purpose of swinging the arm 48 I have provided a toggle joint 51 having one of its links 52 pivoted to the arm 48 and the other toggle link 53 pivotally connected to the pressure arm 54 40 mounted on a pin 55 in the bracket 44. A lever 56 has been secured to a rotatable pin 57. At the lower end of the pin 57 has been secured a crank arm 58 which is pivotally secured to a toggle operating link 59. The link 59 is pivotally connected to the links 52 and 53. It is thus possible to swing the lever 56 and the crank arm 58 and the toggle operating link 59 so as to align the two toggle links 52 and 53 and cause a pressure between the rotary cutter 19 and the ball bearing 20.

It is to be noted that the horizontally swinging arm 48 permits swinging of one of the pinking members away from the needle 21 and out of tensioned operative engagement and that the roller 55 20 may be the swinging member.

An open coil compression spring 60 faces the free end of the pressure arm 54 and serves to press against said arm. This resilient pressure is transmitted by the toggle joint 51 to the rotary 60 cutter 19 and forces the cutter against the ball bearing 20 into tensioned cutting relation.

An annular casing 61 has been secured at the upper end of the shaft 49. The casing 61 has a chamber 62 serving to house a detent carrier 63, 65 detent rollers 64 and springs 65 which jointly form a friction clutch 66. The rollers press against cam surfaces in the detent carrier 63. An oscillatable arm 68 has been fastened to the detent carrier 63 and which when turned clockwise 70 causes rotation of the rotary cutter 19.

As shown in Figures 10 and 11, a vibrating connection 69 has been secured to the oscillatable arm 68 by a ball joint 70. The other end of the connection 69 has an eccentric strap 71 (Figure 10) which is designed to engage an eccentric 72 5 mounted on the needle-vibrator shaft 73. The needle-vibrator shaft 73 is geared to operate once for every two stitches and the connection 69 causes the oscillatable arm 68 to intermittently actuate the clutch 66 (Figure 11) and the rotary 10 trimmer 19 in timed relation once for every two stitches of the sewing machine.

As shown in Figure 10, there has been provided a friction clutch 75 having clutching members similar to that of the actuating clutch 66 but 15 interposed between the actuating clutch and the rotary cutter. The clutch 75 serves to grip the shaft 49 the moment it is released by the clutch 66 and prevents retrograde movement of the cutter 19. 20

As shown in Figure 10, the pinking mechanism 18 is secured to the head 45 of a Singer 107W zig-zag sewing machine in such a manner as to cause the rotary members 19 and 20 to be respectively positioned on each side of the needle 21. 25 The pinking mechanism 18 is thus transverse to the line of stitching of the sewing machine. As shown in Figures 1 and 10, the pinking members 19 and 20 are positioned in advance of the needle 21 and entirely above the work supporting base 30 12. The rotary pinking members are mounted to rotate in a horizontal plane in spaced relation above the base and with their shafts in a plane mounted in angular relation with the sewing machine base. 35

It is to be noted that the method disclosed herein differs from the disclosure in my patent application Serial No. 747,824, filed October 11, 1934, in that an additional step is herewith disclosed, that of blowing the pinked clippings away 40 from the line of stitching.

I claim:

1. The method of forming a flat, ornamented and non-ravelling elastic seam for sewed articles, which comprises turning up the edges of two flat 45 sections of fabric into adjoining relation, in pinking both upturned edges simultaneously, in blowing the pinked clippings away from the line of stitching, in downfolding the pinked edge of one of said sections, in flattening the pinked edge of 50 the other section over said folded edge and causing said pinked edges to lay flat in superposed relation and then stitching said edges together by a single line of zig-zag stitching passing through both sections of said fabric. 55

2. The method of forming a trimmed and non-ravelling seam substantially flat on its normally exposed surface, which comprises turning up the edges of two flat sections of fabric into adjoining relation, in trimming both upturned edges, in 60 blowing the trimmed clippings away from the line of stitching, in downfolding the trimmed edge of one of the sections, in flattening the trimmed edge of the other section over said folded edge and causing said trimmed edges to lay flat in 65 superposed relation and then stitching said edges together by a single line of zig-zag stitching passing through both sections of said fabric.
